UNITED STATES PATENT OFFICE.

WALTER J. PATON, OF GALVA, KANSAS.

BOX.

No. 892,299.

Specification of Letters Patent.

Patented June 30, 1908.

Application filed March 4, 1908. Serial No. 419,070.

To all whom it may concern:

Be it known that I, WALTER J. PATON, citizen of the United States, residing at Galva, in the county of McPherson and State 5 of Kansas, have invented certain new and useful Improvements in Boxes, of which the following is a specification.

The object of this invention is an improved box which is designed particularly for shipping purposes and the like, which is solid in structure, and which is adapted to be knocked down when not in use, so as to be compact in form.

With this and other objects in view that 15 will more fully appear as the description proceeds, the invention consists in certain constructions and arrangements of the parts that I shall hereinafter fully describe and claim.

20 For a full understanding of the invention and the merits thereof, and also to acquire a knowledge of the details of construction and the means for effecting the result, reference is to be had to the following description and 25 the accompanying drawing, in which:

Figure 1 is a perspective view, partly broken away, of my improved box; Fig. 2 is a section on the line 2—2 of Fig. 1; Fig. 3 is a section on the line 3—3 of Fig. 1; and, 30 Fig. 4 is a perspective view of the sides and ends of the box detached.

Corresponding and like parts are referred to in the following description and indicated in all the views of the drawing by the same 35 reference characters.

My improved box embodies two sides 1 and two ends 2 which are formed at their meeting edges with perpendicularly disposed corner portions 3, the corner portions of the 40 ends 2 overlapping the sides 1, and the corner portions of the sides bearing against the inner faces of the ends. The sides 1 are formed at their lower edges with laterally and inwardly disposed flanges 4, the extremities of which extend outwardly beyond the ends 2 and are bent upwardly against the outer faces thereof, as shown, said sides being formed at their upper edges with outstanding rims 5 that form abutments for the 45 overlapping corner portions 3 of the ends 2, to prevent the latter from being slipped upwardly out of engagement with the sides. The ends 2 are formed at their upper edges with flaps 6 that are returned inwardly upon 50 such ends and embrace the corner portions 3 of the sides, to hold the latter securely to

the ends and form a solid structure. The bottom 7 of this box rests upon the inwardly disposed flanges 4 of the sides 1, as shown.

A top 8 is employed to close the box, and 60 has its side edges returned inwardly, as indicated at 9, and adapted for engagement with the outstanding rims 5 of the sides to slidingly connect the top to the box, said top being preferably provided at one end 65 with a depending lip 10 which is adapted to abut against the adjacent end 2 of the box and form a stop to limit the sliding movement of the top.

In the practical use of this improved box, 70 when it is desired to knock down the latter, the top and bottom of the box are removed, and the outstanding rims 5 of the sides are bent to lie in the same plane with the latter, the ends being then slipped out of engagement with the sides to separate the box into its various parts. When the parts of the 75 box are separated, they are preferably bent flat, so as to be compact in form.

From the above description, in connection 80 with the accompanying drawing, it will be apparent that I have provided a simple, durable and efficient construction of box which may be formed of papier-mâché, fiber or other suitable material, and the parts of 85 which may be securely fastened together without the use of nails or other similar fastening means.

Having thus described the invention, what I claim is:

1. A box comprising sides and ends having angularly disposed corner portions, the corner portions of the ends overlapping the sides, and the corner portions of the sides bearing against the inner faces of the ends, 95 the sides being formed at their lower edges with inwardly disposed flanges, the extremities of which extend outwardly beyond the ends and are bent upwardly against the latter, said sides being also formed at their upper edges with outstanding rims, the ends being formed at their upper edges with flaps returned inwardly and embracing the corner portions of the sides, and a bottom supported by the flanges of the sides. 100

2. A box comprising sides and ends having angularly disposed corner portions, the corner portions of the ends overlapping the sides, and the corner portions of the sides bearing against the inner faces of the ends, the 110 sides being formed at their lower edges with inwardly disposed flanges, the extremities of

which extend outwardly beyond the ends and are bent upwardly against the latter, said sides being also formed at their upper edges with outstanding rims, the ends being formed at their upper edges with flaps returned inwardly and embracing the corner portions of the sides, a bottom supported by the flanges of the sides, and a top formed with returned edges designed for sliding engage-

ment with the outstanding rims, and with 10 a depending lip adapted to limit the sliding movement of the top.

In testimony whereof I affix my signature in presence of two witnesses.

WALTER J. PATON. [L. s.]
